DESIGN FOR A WALL TELEPHONE

Herbert F. Obergfell, River Forest, Ill., assignor to Associated Electric Laboratories, Inc., Chicago,
Ill., a corporation of Delaware

Application November 9, 1934, Serial No. 53,956

Term of patent 14 years

To all whom it may concern:

Be it known that I, Herbert F. Obergfell, a citizen of the United States of America, residing at River Forest, Cook County, Illinois, have invented a new, original, and ornamental Design for a Wall Telephone, of which the following is a specification, reference being had to the accompanying drawing, forming a part thereof.

The figure is a perspective view of a wall telephone, showing my new design. The opposite side is like the side shown, while the rear is a substantially plain vertical surface.

I claim:

The ornamental design for a wall telephone as shown and described.

In testimony whereof, I have hereunto set my hand this 7th day of November, 1934.

HERBERT F. OBERGFELL.
